UNITED STATES PATENT OFFICE.

HOWARD E. PARKINSON, OF BALFOUR, NORTH CAROLINA.

SHAFT TRUING AND GRINDING DEVICE.

Application filed September 7, 1922. Serial No. 586,659.

To all whom it may concern:

Be it known that I, HOWARD E. PARKINSON, a citizen of the United States of America, residing at Balfour, in the county of

5 Henderson and State of North Carolina, have invented new and useful Improvements in Shaft Truing and Grinding Devices, of which the following is a specification.

10 The object of the invention is to provide a relatively simple and efficient means for truing the journal portions of shafts and particularly of crank shafts and more especially the pitman rod journal portions of 15 crank shafts which are used in connection with internal combustion motors and the like; and with this object in view the invention consists in a construction and combination of parts of which a preferred embodiment is shown in the accompanying drawings, wherein:—

Figure 1 is a plan, and

Figure 2 is a side view of an apparatus embodying the invention as seen when applied to a crank shaft.

Figure 3 is a sectional view on the plane indicated by the line 3—3 of Figure 1.

Figure 4 is a detail view of the liner guide.

20 The apparatus consists of a main guide 10 provided at one end with a bearing jaw 11 and having mounted thereon a carriage 12 movable by means of a manually operable feed screw 13 swiveled at 14 on the guide bar and carrying a grinder head 15 of which the shaft 16 is actuatable by a motor 17 also supported by the carriage. The grinder head consists of or is provided with an emery disk 18 which by the adjustment 25 of the carriage is movable toward and from a bearing head 19 carried by the jaw 11 so as to contact with diametrically opposite portions of the surface of the journal portion 20 of a crank shaft 21 or the equivalent thereof. Also carried by the guide bar is a bearing block 22 adjustable by means of a manually operable feed screw 23 toward and from a center line connecting the grinding and bearing heads, so as to be adaptable 30 in position to the diameter of the shaft journal which is to be ground and properly position the axis of said journal with relation to the line of the axis of the grinder head. The shaft of the grinder head is 35 preferably provided with a flexible section 24 consisting of a coiled spring and serving

as a cushioning means to avoid injury to the shaft journal which is being ground and at the same time maintain a yielding tensioned pressure thereon.

60 The crank shaft of which the journals are to be trued or ground is preferably accurately supported for rotation by center points 25 arranged in a suitable supporting frame such, for example, as that indicated at 26 and in connection with the guide bar of the apparatus there is employed a liner guide 27 secured to the main guide by means of a clamp 28 or its equivalent and having an arm 29 provided with terminal spaced jaws 30 and 31 to engage the aligned journal of the crank shaft so as to maintain the apparatus in a position to insure the axial alignment of the corresponding connecting rod journal. The jaw 31 of the liner guide 75 is adjustable toward and from the other and is adapted to be secured in its adjusted position by means of a set screw 32 or the equivalent thereof.

70 Rotary motion being communicated to the 80 grinder head from the motor or from any other source of energy (it being obvious that while preferably arranged on the carriage the motor does not necessarily constitute an inseparable part of the mechanism) and the 85 apparatus being applied to the properly supported crank shaft in such a way as to dispose the grinding face of the head, the opposed bearing head of the jaw 11 and the bearing block 22 in contact with the surface of the journal to be ground or trued, it will be obvious that the rotation of the 90 crank shaft with relation to the apparatus or the swinging of the apparatus around the crank shaft journals which are engaged respectively by the grinding means and the 95 jaws of the liner guide, will bring the face of the grinder head into contact progressively with all portions of the surface of the journal to reduce any irregularity there- 100 in and restore it to a perfectly round condition so that by the employment of suitable bearing sleeves or packing or by the adjustment of the bearing, an accurate mounting of the pitman or connecting rod may be 105 made thereon.

Having described the invention, what is claimed as new and useful is:—

1. A truing apparatus for shaft journals having a guide provided with a bearing jaw, 110 and a revoluble grinder head movable toward and from and having its axis arranged

in angular relation with the plane of the bearing jaw, means being provided for communicating rotary motion to the grinder head and the latter having means for effecting a yielding tensioned pressure on the journal being ground.

2. A truing apparatus for shaft journals having a guide provided with a bearing jaw, and a revoluble grinder head movable toward and from and having its axis arranged in angular relation with the plane of the bearing jaw, means being provided for communicating rotary motion to the grinder head, a carriage being mounted upon the said guide and having bearings for the shaft of the grinder head, and a motor supported by the guide and having a flexible shaft connection with that of the grinder head.

3. A truing apparatus for shaft journals having a guide provided with a bearing jaw, and a revoluble grinder head movable toward and from and having its axis arranged in angular relation with the plane of the bearing jaw, means being provided for communicating rotary motion to the grinder head, in combination with a liner guide carried by said first-named guide and

provided with jaws for engaging an aligned journal of the shaft.

4. A truing apparatus for shaft journals having a guide provided with a bearing jaw, and a revoluble grinder head movable toward and from and having its axis arranged in angular relation with the plane of the bearing jaw, means being provided for communicating rotary motion to the grinder head, in combination with a liner guide carried by said first-named guide and provided with jaws for engaging an aligned journal of the shaft, one of the jaws of the liner guide being adjustable with relation to the other.

5. A truing apparatus for shaft journals having a revoluble grinder head and means for positioning the same to effect a grinding operation on a shaft journal, in combination with a guide operatively connected with said means and attachable to a remote aligned journal to insure the grinding of the journal being operated upon being aligned with said remote journal.

In testimony whereof he affixes his signature.

HOWARD E. PARKINSON.
